UNITED STATES PATENT OFFICE.

THOMAS J. KEHOE, OF TOLEDO, OHIO, ASSIGNOR TO THE WILLYS-OVERLAND COMPANY, OF TOLEDO, OHIO, A CORPORATION OF OHIO.

RADIATOR.

1,410,102.

Specification of Letters Patent. Patented Mar. 21, 1922.

Application filed June 4, 1917. Serial No. 172,758.

To all whom it may concern:

Be it known that I, THOMAS J. KEHOE, a citizen of the United States, residing at Toledo, in the county of Lucas and State of Ohio, have invented certain new and useful Improvements in Radiators, of which I declare the following to be a full, clear, and exact description.

This invention relates to removable closures, and particularly closures for use in closing the filling openings in radiators for motor vehicles.

The principal object of my invention is to provide a removable closure which is normally held in position covering the openings by means of spring tension. Another object of my invention is to provide a radiator cap construction such that the cap is permanently attached to the radiator, may be swung to open position without disconnecting any part, and is resiliently held in open position.

Further objects, and objects relating to details of construction and economies of manufacture, will definitely appear from the detailed description to follow.

I accomplish the objects of my invention by the devices and means described in the following specification. My invention is clearly defined and set forth in the appended claims.

A structure constituting a preferred embodiment of my invention is illustrated in the accompanying drawing, forming a part of this specification, in which:

Figure I is a fragmentary, front elevation of an automobile radiator provided with a radiator cap embodying my invention.

Figure II is an enlarged, sectional view, taken on the line II-II of Fig. I, and showing the cap in closed position.

Figure III is a view similar to Figure II, but showing the cap in open position.

Figure IV is a detail, sectional view, taken on the line IV-IV of Figure III, showing the hinge connection.

Figure V is a detail, sectional view, similar to Figure II, showing a modified form of my invention.

Figure VI is a view, similar to Figure V, but showing the cap in open position.

Figure VII is a detail, fragmentary view in side elevation, showing a portion of the locking and tensioning means.

Figure VIII is an enlarged, detail, frag-

mentary view taken on the line VIII-VIII of Figure V.

In the drawings, similar reference numerals refer to similar parts throughout the several views and the sectional views are taken looking in the direction of the little arrows at the ends of the section lines.

Considering the numbered parts of the drawings, the automobile radiator 1 has the usual filling nozzle 2 provided with a rim 2'. Cap 3 is provided for closing the nozzle 2 and stem 4 is slidably mounted in an opening extending centrally through said cap 3. The lower end of said stem 4 is bent at substantially right angles to the body thereof and is connected to the side of the nozzle 2 by means of the pintle 5, which passes through the end of the stem 4 and is carried by the yoke 11 attached to the side of the nozzle by the rivets 12. The stem 4 extends upwardly through the cap 3 and the washer 6 is secured to the upper end of the stem by the screw 7. Spring 8 is compressed between the washer 6 and the upper end of a cylindrical boss 9 which is formed on the cap 3. A guard or housing 10 surrounds the upper end of the stem 4 and the spring 8, and is threaded on to the cylindrical boss 9. This guard serves to house and protect the stem 4 and the spring 8, and also serves as a handle by which the top may be swung to one side when the filling opening is to be uncovered.

When the cap 3 is in the position shown in Figure II, the spring 8, acting on the cap 3, serves to normally press it downwardly in engagement with the rim 2' of the nozzle 2, so that the cap is yieldingly held in engagement therewith. Cap 3 can be tilted or moved laterally against the tension of the spring 8 and when the cap has been moved to one side to uncover the opening, the spring will tend to hold the cap 3 against the side of the nozzle 2, as shown in Figure III. The co-operative action of the spring 8 and bent stem 4 results in the closure being positively held in either open or closed position, since, as shown in Figure III when the stem is tilted from its normal upright position, the base of the closure is pressed firmly against the outer side of the nozzle 2 and the closure held at one side of the nozzle opening, while, as shown in Figure II, when the stem is in upright position, the closure is clamped firmly upon the rim 110

2' of the nozzle 2 by the action of the spring 8. To close the opening, the cap is merely moved back to its former position and spring 8 holds it firmly in position over the opening. The cap is permanently attached to the radiator and is always held in yielding engagement with the nozzle so that there is no chance for it to rattle or work loose.

- 10 In Figures V to VIII inclusive, I have shown a modified form of my invention in which a downwardly curved yoke 14 is secured inside the nozzle 2. This yoke is provided with a central slot 15, as appears from 15 Figures VI and VIII. The cap 17 has the stem 16 slidably mounted therein, and is provided at its upper end with a handle 22. Yoke 20 is fastened to the cap 17, and provided with a central opening through 20 which the stem 16 passes and the spring 21 is compressed between said yoke 20 and a shoulder 19 formed on the stem 16. A bar 23 extends downwardly and laterally from the stem 16, passing through the slot 15 in the yoke 14, and said bar is provided at its 25 upper end with shoulders 24 which are adapted to engage notches 25 formed in the edges of the opening 15 in the yoke 14. A flat leaf spring 26 is secured to said bar 23 by the screws 27 and is adapted to engage 30 the edge of the opening 15, when the top is raised to open position, the end of said spring being provided with a laterally bent portion 28 which serves to hook the edge 35 of the opening 15 to prevent complete removal of the cap. In Figure VI the top is shown in its open position and, to close the opening, the cap is moved into position over the opening and the stem 16 is forced downwardly until the shoulders 24 are below the yoke 14. The handle 22 is then given a partial turn which brings the shoulders 24 into engagement with the notches 25 in the edges of the opening 15, and the handle is then 40 released, the spring 21 bringing the shoulders 24 into positive engagement with the yoke 14 so that the cap is yieldingly but positively held in position. To remove the closure it is merely necessary to depress the 45 handle 22 against the tension of spring 21 and to give the handle a partial turn so as to bring the bar 23 into alignment with the slot 15, when the spring 21 will force the cap and the stem 16 upwardly.
- 50 I have shown my invention embodied in a radiator cap construction, but it will be evident that this invention is applicable equally as well to other constructions in which it is desirable to provide a closure which is held 55 in position by spring tension and permanently attached to the part which it serves to close so that it can not become separated therefrom and lost, and therefore, I do not desire that my claim should be considered 60 as limited to a radiator cap construction.

I have found that the preferred embodiment of my invention, which I have here described, is desirable from many standpoints, but I am aware that other embodiments of the invention are possible and that the embodiment here shown may be varied considerably without departing from the spirit of my invention, and, therefore, I desire to claim my invention broadly, as well as specifically, as indicated by the appended 70 claims.

Having thus described my invention, what I claim as new and desire to secure by Letters Patent is:

1. In a device of the class described, the 80 combination of a nozzle, a stem pivotally connected to said nozzle, a closure for such nozzle mounted upon said stem and slidably bodily with respect thereto, and spring means between said stem and said closure yieldingly holding said closure in place on said nozzle.

2. In a device of the class described, the combination of a nozzle, a stem pivotally connected to said nozzle, a closure for said 90 nozzle mounted upon said stem and slidably bodily with respect thereto, a shoulder on said stem, and a coiled spring mounted on said stem between said shoulder and a part of said closure, said spring yieldingly holding said closure in position on said nozzle.

3. In a device of the class described, the combination of a nozzle; a closure for said nozzle; a stem extending through said closure and slidably therein; a hinge connection between the inner end of said stem and the side of said nozzle; and a spring compressed between said closure and the upper end of said stem and yieldingly holding said closure in position on said nozzle.

4. In a device of the class described, the combination of a nozzle; a closure therefor; a stem extending through and slidably in said closure, the lower end of said stem being bent at substantially right angles to the body thereof and pivotally connected to the side of said nozzle; and a spring compressed between the upper surface of said closure and a shoulder on said stem and yieldingly holding said closure in place on said nozzle.

5. In a device of the class described, the combination of a nozzle; a closure therefor; a stem extending through and slidably mounted in said closure, the lower end of said stem being bent at substantially right angles and pivotally connected to the side of said nozzle; a spring on the upper end of said stem, compressed between said closure and a shoulder on said stem and normally holding said closure seated on said nozzle; and a housing carried by said closure and enclosing the upper end of said stem and spring.

6. In a device of the class described, the combination of a nozzle; a closure therefor; 130

5 a stem hinged to the inner side of said nozzle on which said closure is slidably mounted; and a spring means engaging said stem and closure and tending to hold the latter yieldingly in position on said nozzle.

6 7. In a device of the class described, the combination of a nozzle, a stem bent at substantially right-angles and pivotally mounted within said nozzle, a closure centrally 10 mounted to slide on said stem, and means for holding the closure seated upon the nozzle.

11 8. In a device of the class described, the combination of a nozzle, a closure therefor, and means connecting the closure with the 15 inner surface of the nozzle adapted to retain the closure in either open or closed position.

9. In a device of the character described, the combination of a nozzle, a stem pivoted 20 upon the inner surface of the nozzle, a closure carried thereby, and resilient means for holding the closure in either open or closed position.

10. In a device of the class described, in 25 combination, a nozzle, a stem pivoted upon the inner surface of the nozzle, a closure slidable thereon, and resilient means for holding the closure in open position against

the side of the nozzle or in closed position upon the nozzle. 30

11. In a device of the class described, the combination of a nozzle, a stem having a laterally extending lower end pivoted to the nozzle interiorly thereof, and a closure for said nozzle slidable upon said stem, the 35 parts being so proportioned and arranged that said stem may be swung to horizontal position over the edge of the nozzle, and resilient means tending to hold said closure upon the end of the nozzle or against one 40 side thereof, depending upon the position of the stem.

12. In a device of the class described, the combination of a nozzle, a substantially central stem having a laterally extending lower 45 end pivoted to the nozzle interiorly thereof, and a closure for said nozzle slidable upon said stem, the parts being so proportioned and arranged that said stem may be swung to horizontal position over the edge of the 50 nozzle, and resilient means tending to hold said closure upon the end of the nozzle or against one side thereof, depending upon the position of the stem.

In testimony whereof I affix my signature. 55
THOMAS J. KEHOE.
